UNITED STATES PATENT OFFICE.

FRANK YOKEL, OF AVALON, PENNSYLVANIA.

HEATING STOVE.

Application filed December 22, 1923. Serial No. 682,192.

To all whom it may concern:

Be it known that I, FRANK YOKEL, a citizen of the United States, residing at Avalon, in the county of Allegheny and State of Pennsylvania, have invented certain new and useful Improvements in Heating Stoves, of which the following is a specification.

This invention is for an improvement in 10 gas heating stoves of the open front type, in which combustion takes place in a series of vertical open front columns or "radians," as they are termed in the art.

The present invention has for its principal object to provide a stove wherein the several radians are formed of two pieces of sheet metal, instead of being individually molded from fire clay, as is customary, and with the radians so designed as to provide 15 a maximum radiating surface. The invention has for a further object to provide for the circulation of air around the radians and out the top of the stove, whereby heating by convective currents is obtained and 20 the efficiency of the stove increased.

The invention may be readily understood by reference to the accompanying drawings, in which:

Fig. 1 is a front view, partly in section 30 and partly in elevation;

Fig. 2 is a vertical transverse section in the plane of line II—II of Fig. 1;

Fig. 3 is a horizontal section in the plane of line III—III of Fig. 2; and

Fig. 4 is a transverse section on a large scale of a portion of the two plates forming the radians.

In the drawings, 5 designates the front bottom frame member of the stove, and 40 6 are legs formed integrally therewith. Supported on this front member, and on rear legs 7, is a sheet metal casing having a back 8, sides 9, a top 10, and a depending front coping 11. The front of the coping is perforated at 12.

Also, partially supported on the member 5, is a horizontal plate 13 having a row of large holes 14 therein, to the rear of which is a second row of smaller holes 15. Below 50 the plate 13 is a manifold 16 having a row of burners 17 on the top thereof, one burner projecting into each hole 14.

The several hollow open front columns or radians 18, which extend up from each 55 hole 14, are formed of two sheets of metal 19 and 20 having outwardly pressed verti-

cal ribs 21 therein, the ribs of one plate registering with those of the other. The columns are spaced apart from each other, as shown in Fig. 3, so that each column is 60 well removed from the adjacent ones; the areas of the plate between the ribs meet at the intervening space. This arrangement gives a large area with which air currents may contact to obtain efficient results. The 65 ribs of the front sheet 19 are pierced as at 22 to form an ornamental grille. When the metal is pierced at 20, it is not entirely cut away, but is forced inwardly, as at 23, to provide heat absorbing projections inside 70 the column.

Within the upper part of the stove is a hood 24, into which the top of the radians project. This hood, extending from one end of the stove to the other, is spaced 75 away from the top and back walls of the stove, and has a central rearwardly extending outlet 25 which may connect with a suitable pipe to a flue. Being spaced away from the top and rear of the top part of the stove, the hood serves to heat air in the top part of the stove, from whence it passes into the room through the perforations 12. Fresh air, at the bottom of the stove, rises 80 in back of the radians, circulating around them and into the top of the stove. In this manner, the air in a room may be heated by contact with the heated parts of the stove, and the heat of combustion distributed without mingling the products of 85 combustion or unburnt gases with the air.

A stove as thus constructed is simple and rigid, and may be cheaply manufactured. If desired, the radians may be painted white to render the stove more attractive. Copper reflectors may be placed at each side of the open front of the stove, as indicated at 26.

I claim as my invention:

1. A stove comprising a casing, a plurality of burners in the lower part thereof, and a pair of vertical plates mounted over the burners having separated oppositely pressed vertical ribs therein, the ribs of one plate registering with those of the other whereby vertical hollow columns are formed, one of said columns being disposed over each burner, the ribs of the plates being separated by intervening flat areas whose inner faces contact.

2. A stove comprising a casing having an open front, a rear wall, and a hollow perfo-

rated upper portion, a plurality of burners in the lower part of the stove, radiants extending upwardly from the burners, said radiants being spaced forwardly of the rear 5 wall of the casing and providing an air circulating space between the radiants and the rear wall and in which air may contact directly with the radiants, a hood in the upper hollow part of the stove having a flue connection, said hood being spaced from the back wall of the casing, said radiants extending into the hood, the back space at the rear of the radiants extending upwardly past the hood whereby air heated in the 10 air space by direct contact with the radiants may flow out the perforated top of the stove while the gases of combustion from the radiants may be carried out the flue.

3. A stove comprising a casing having an 15 open front, side and back walls, and a hollow top portion, of a horizontal supporting member in the lower part of the stove, a row of spaced apart burners in openings in the supporting member, a pair of vertical plates mounted on the supporting member over the burners, said plates having contacting faces in which are oppositely pressed 20 ribs to form hollow columns between the plates, one of the plates having said ribs 25 perforated, said ribs on each plate being spaced apart, with the columns being positioned over the burners, a hood in the hollow upper part of the stove into which the gases from the columns may pass, said hood having 30 a flue outlet therein, the hood being spaced from the top and rear walls of the upper part of the casing, a continuous air 35

passage being provided at the back of the plates from the top to the bottom of the stove, and perforations in the top part of the 40 casing through which air passing through the space behind the burners and in contact with the hood may emerge into the room, the plates forming a partition between the front and back of the stove. 45

4. Radians for heating stoves comprising a pair of adjacent plates having registering oppositely formed vertical channels therein, which channels are spaced apart from those at each side thereof, having flat surfaces being provided between the channels of the respective plates which contact with the corresponding flat surfaces of the other plate, the channels of one of the plates being perforated, the said channels at each side of the 50 plate being separated so as to permit of the circulation of air thereabout.

5. A radiant element for heating stoves comprising a pair of sheet metal plates having oppositely pressed ribs formed therein, the ribs of each plate having sides which are spaced away from those of the next adjacent plate, intervening flat surfaces being provided between the ribs, the ribs and flat surfaces of the two plates registering thereby 60 forming separated hollow columns with the respective flat surfaces contacting, the ribs of one plate having perforations therein, the metal removed by perforating being only 65 partially severed and projecting into the hollow columns.

In testimony whereof I affix my signature.

FRANK YOKEL
